Jones, Addington, Cimex, ATTORNEYS.
Seibold

UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

FUSE PLUG.

Application filed June 2, 1919. Serial No. 301,265.

To all whom it may concern:

Be it known that I, REUBEN B. BENJAMIN, a citizen of the United States, residing at Chicago, in the county of Cook and State of Illinois, have invented new and useful Improvements in Fuse Plugs, of which the following is a full, clear, concise, and exact description, reference being had to the accompanying drawing, forming a part of this specification.

The present invention relates generally to fuse plugs for electric circuits, and more particularly to fuse plugs in which the fuse may be viewed through a transparent member and in which the fuse element is renewable.

One of the objects of my invention is to provide an improved fuse plug which is provided with indicating means for indicating when a fuse is blown, the indicating means being renewable so that a new indicating means can be provided each time a fuse is blown.

Another object of my invention is to provide an improved fuse plug provided with a renewed fuse and a renewable indicating means in which the fuse and indicating means are combined in a unitary device, which unitary device can be removed when the fuse is blown and replaced by a new device having a fuse and indicating means.

Another object of the invention is to provide a fuse plug of this class which shall be simple in construction, durable and efficient in operation, and economical to manufacture.

The various features and advantages of the invention will be more fully understood upon referring to the following description taken in connection with the accompanying drawing, while the scope of the invention will be particularly pointed out in the appended claims.

In said drawing,

Fig. 1 is a plan view of a fuse plug constructed in accordance with the present invention;

Fig. 2 is a bottom plan view of the renewable element of the plug;

Fig. 3 is a vertical section of the renewable element taken on a plane indicated by the line 3-3 of Fig. 2;

Fig. 4 is a vertical section of the complete structure taken on a plane indicated by the line 4-4 of Fig. 1;

Fig. 5 is a plan view of the insulating body with the center contact connecting strip in position;

Fig. 6 is a bottom plan view of the complete plug;

Fig. 7 is a perspective view of the upper portion of one element of the shell member as it appears before being assembled with the other parts of that member;

Fig. 8 is a vertical section of a portion of the plug taken on a plane indicated by the line 8-8 of Fig. 1; and

Fig. 9 is a perspective view of one of the spring clips by which the shell member is secured to the insulating body. Throughout these views like characters refer to like parts.

Referring to the drawing in detail, the main plug member A includes the insulating body 10 and the connecting strip 11 which terminates at one end in a center contact 12 and at the other end in a fuse engaging portion 13; B designates the renewable fuse element and C designates the shell member which holds the fuse element in place, and provides the shell contact 14 of the plug.

The insulating body 10 may be composed of any suitable insulating material. Ordinarily porcelain will be used for this purpose and the body will be molded in the shape shown. In the particular form herein disclosed the body 10 includes a circular wall 15, a transverse partition 16, and an end 17. Vents 18 and 19 are located in the end 17 to allow the escape of gases from the chambers 20. The vent 19 also serves as an opening for the insertion of the conducting strip 11. This strip is composed of conducting material and is given the shape more particularly shown in Fig. 4.

When so shaped the inner end 13 may be passed through the vent 19 and then the strip shoved upward until the end 13 slips over the end of the wall 15 and finally rests in the recess 21 formed for it in the wall. When the strip has been put in this position it bears near its center against one side of the partition 16, at its upper end against

the wall 15, and at its lower end against the side of the opening 19. The lower end of the strip is given an angular turn 22 which causes the lower end of the strip to fit snugly over a projecting portion 23 on the lower face of the insulating member 10. In this way, the end of the conducting strip 11 forms the center contact 12 of the plug and the upper end provides the bearing and contact face 13.

The removable fuse and indicating element B comprises an insulating member 24 which is provided with an elongated central opening, a fuse strip 25, and a sheet 26 of transparent insulating material such as mica which is secured to one face of the insulating member 24, through which the fuse strip 25 located upon the other side of member 24 may be viewed. This sheet of mica forms an indicating means, the mica being blackened by the blowing of the fuse, so that it can easily be determined, without taking the plug out of the socket or taking it apart, when the fuse has been blown. As the fuse and window are combined in a unitary device, when a new fuse is put in, a new window is also put in. Thus a clean window means that the fuse has not been blown, and a blackened window means that the fuse has been blown. The strip 25 is composed of any suitable fusible material and is preferably widened at its ends, and those ends are bent over and around the insulating member 24 as clearly indicated at 27 and 28. The ends of the strip thus engage the outer side of the transparent member 26. When the renewable element B is placed in position in the plug, the under side of one end of the strip 25 is firmly seated against the upper face of the end 13 of the conducting strip 11. In this way circuit is completed from the center contact 12 to one end of the strip 25. In order to bring the end of the strip 25 into proper position to engage the end of the contact strip 11, the insulating disk 24 of the member B is provided with a registering opening 29 and registering notches 30 and 31. These notches and openings are fitted over projections upon the upper end of the insulating plug body 10, the opening 29 being fitted over projections 32 and the notches 30 and 31 being fitted over projections 33 and 34 respectively.

The shell member C includes a threaded shell 35, a cap 36 and intervening insulation 37. The shell 35 is composed of conducting material and the threaded portion of the shell, designated 14, forms the shell contact of the plug. The cap 36 which is preferably composed of metal is provided with a central aperture. A sheet of transparent insulating material 38, preferably mica, is fitted into the end of the cap and closes the aperture in the cap through which

sheet the renewable fuse element B may be viewed. The insulation 37 is in the form of a ring which is forced against the disk 38 and lies between the outer surface of the upper end of the member 35 and the skirt or flange of the cap 36. The parts 35, 36 and 37 are first assembled while the engaging portions are cylindrical in form. When thus assembled they are pressed out or deformed at intervals to provide "bumps" 39. By means of these bumps these parts of the shell member are held together. As clearly illustrated, the upper end of the shell 35 is provided with inwardly extending flange 40. When the parts are assembled the under side of this flange engages the end 27 of the fuse strip. This end, as previously noted, lies above the mica or other transparent sheet 26. Consequently an electric connection is provided with the end of the fuse strip 26 and the shell contact 14. The point at which the flange 40 engages the end of the fuse strip is diametrically opposite to that at which the other end of the fuse strip engages the face 13 of the center contact strip 11. Thus one connection is made with the under side of the fusible element B and the other connection is made with the upper side of that element. As clearly shown in Fig. 7, the shell 35 is cut away at 42 so as to keep all portions of the shell 35 far enough away from the end of the strip 11 and the adjacent end of the fuse strip 25 to prevent a short circuit between the center and shell contacts. It will be noted that the cap 36 is separated from the end 28 of the fuse strip by means of the insulating sheet 38.

The shell member C is removably connected to the plug body A so that the two members may be separated in order to replace a used fuse member B. The connection between the members A and C is provided by a plurality of spring strips 43 which extend into channels or grooves 44 formed in the outer face of the wall 15 of the insulating member 10. These strips are preferably given the shape illustrated in Fig. 9. The upper end of the shell 35 is struck up so as to provide inwardly extending projections 45 which have substantially the same cross section as the channels 44. These projections 45 fit into the upper ends of the channels 44 and thus center the entire shell member C with reference to the plug member A. Since these projections are struck up they provide depressions in the outer surfaces of the shell 35, and as clearly shown, the bottom of each of these depressions is open as indicated at 46. The spring strips 43 extend through these openings 46 and lie between the inner wall of the projection 45 and the insulation 37 as particularly illustrated in Fig. 8. By constructing the strips 43 of spring metal the

end of the strip will remain in place between the insulation and the adjacent wall of the shell 35 without being soldered or otherwise connected, although such soldered or other connection may be resorted to if desired. The free end of each of the strips 43 is provided with a curved portion 47 which rides freely upon the bottom of the channel 44 in the wall 15.

10 When the parts are all assembled, the fuse strip 25 rests upon the upper end of the partition or pier 16 as well as upon opposite portions of the wall 15. That portion of the upper surface of the partition 16 which 15 engages the fuse strip 25 is angularly shaped and provides a flat surface 48 upon which the strip 25 rests. When thus in position the end 28 of the fuse strip rests directly upon the end 13 of the center contact strip 20 11. The opposite end of the fuse rests directly upon the wall 15. In order to give a maximum span to the fuse strip, the wall 15 at the latter point is cut away as indicated at 49. With this construction the fuse strip 25 is supported at three points and is therefore likely to fuse at two points when subjected to an undue current in service. These ruptures of the fuse would occur at the open ends of the chambers 20 and the gases resulting from the combustion would escape through the vents 18 and 19. The complete electric circuit through the fuse may be traced from center contact 12 through strip 11, contact face 13, fuse strip 25, shell 35 35 and shell contact 14. The condition of the fuse at any time can be observed through the double sheets 26 and 38. The sheet 26 may be made of light and less durable material than the sheet 38 since the former will 40 be replaced every time a fuse is replaced, while the latter will be used over and over again. When it is desired to replace a fuse all that is necessary is to withdraw the member C outward away from the member A 45 and thus draw the spring strips 43 out of the channels 44. The used element B may then be taken from the plug and a new element B inserted. In inserting the latter it is only necessary to have the registering notches 50 30 and 31 and opening 29 fit over the corresponding projections 33, 34 and 32 on the body 10. The shell member C may be replaced by simply bringing the strips 43 into the channels 44 and forcing the parts together. At any time the entire plug may be 55 screwed into or out of a socket without in any way changing the relation of the various parts.

It will be understood that in carrying out 60 my invention certain alterations and modifications may be made in the structure herein shown and described without departing from the spirit and scope of my invention. Other modifications will readily suggest 65 themselves to persons skilled in this art.

What I claim as new and desire to secure by Letters Patent of the United States, is:

1. A removable fuse element comprising an apertured insulating disc, a transparent sheet extending across the aperture in said disc, and a fuse strip secured to said disc and extending parallel to said sheet in position to be seen through it.

2. A removable fuse element comprising an apertured insulating member, a transparent covering for said aperture, and a fuse strip secured to said member and visible through said covering.

3. A removable fuse element comprising an apertured insulating member, a transparent sheet covering said aperture on one side of said member, a fuse strip extending over said aperture on the other side of said member and having its ends bent around said member so as to lie on the said side thereof as said sheet.

4. A fuse plug for electric circuits comprising an insulating body having an open end, a removable fuse element positioned upon the open end of said body, said element having a fuse strip and a transparent sheet for viewing said strip, a shell contact element positioned on said body to hold said fuse element in place, said shell contact element also having a transparent sheet 95 through which said fuse element may be viewed, a center contact on said body, and connections between the ends of said fuse strip and the shell contact and center contact respectively.

5. A fuse plug for electric circuits comprising an insulating body, a center contact secured to said body, a shell contact removably secured to said body, and a renewable fuse element held between said shell and 105 body, said element having a fuse strip and a transparent sheet for inspecting the same.

6. A fuse plug for electric circuits including an insulating member, an insulating fuse support, a fuse spanning an aperture in 110 said support and having its ends bent around said support so as to be on the opposite side thereof from the body of said fuse. A window in said support for viewing said fuse, a shell removably secured to said member and operative to hold said fuse and its support in place, said shell forming an electrical connection with said fuse at one side of said support, a center contact strip carried by said insulating member and making 120 electrical contact with said fuse on the other side of said support.

7. A fuse plug comprising a threaded shell contact, a center contact, an insulating body on which said contacts are mounted, 125 and a unitary renewable device comprising both a fuse and a transparent member located adjacent said fuse through which said fuse is visible, which member is blackened by the fuse when the fuse is blown, so 130

that the fuse and the transparent member can be removed together and replaced by a new unitary device having a new fuse and an unblackened transparent element, 5 said unitary renewable device being readily detachable as a unit from said plug.

8. A fuse plug comprising a threaded shell contact, a center contact, an insulating body on which said contacts are mounted, 10 and a unitary renewable device comprising both a fuse and a transparent member located adjacent said fuse through which said fuse is visible, which member is blackened

by the fuse when the fuse is blown, so that the fuse and the transparent member can be 15 removed together and replaced by a new unitary device having a new fuse and an unblackened transparent element, said unitary renewable device being readily detachable as a unit from said plug, said unitary device being held in place on said plug by means of said threaded shell contact. 20

In witness whereof, I have hereunto subscribed my name.

REUBEN B. BENJAMIN.
